W. F. THOMPSON, DEC'D.
V. A. S. THOMPSON, ADMINISTRATRIX.
NON-REFILLABLE BOTTLE.
APPLICATION FILED NOV. 26, 1913.

1,157,735.

Patented Oct. 26, 1915.

UNITED STATES PATENT OFFICE.

WILLIAM F. THOMPSON, DECEASED, LATE OF NEW YORK, N. Y., BY VIOLA A. S. THOMPSON, ADMINISTRATRIX, OF ROCHESTER, NEW YORK, ASSIGNOR TO OSCAR A. LOGAN, OF NEW YORK, N. Y.

NON-REFILLABLE BOTTLE.

1,157,735.

Specification of Letters Patent. Patented Oct. 26, 1915.

Application filed November 26, 1913. Serial No. 803,136.

To all whom it may concern:

Be it known that WILLIAM F. THOMPSON, deceased, who in his lifetime was a citizen of the United States, and a resident of the 5 city of New York, in the county and State of New York, did invent certain new and useful Improvements in Non-Refillable Bottles, of which the following is a specification.

10 This invention relates to non-refillable bottles.

It seeks to provide an efficient and reliable device and one which can be manufactured and assembled at a reasonable cost.

15 Heretofore, various designs of non-refillable bottles have been proposed but they have nearly all been impracticable because their structures were of such nature as to involve an excessive cost in the manufacture. 20 Many of them have been unable to successfully resist attempts to refill the bottle.

In the present invention the structure is not only capable of efficiently resisting efforts to refill the bottle, but the structure is 25 so designed that it is capable of being manufactured and assembled at a comparatively small cost.

30 In the drawings forming part of this specification, Figure 1 is a sectional elevation of the upper portion of a bottle to which the invention is applied, the bottle being in upright position. Fig. 2 is a similar view showing the bottle tilted and the 35 cork removed for outflow of the liquid. Fig. 3 is a side elevation of the valve case removed. Fig. 4 is a plan view of the cap for the upper end of the valve case. Figs. 40 5, 6 and 7 are sectional plan views taken on the lines 5—5, 6—6, and 7—7, respectively, of Fig. 1.

45 Referring now to the structure shown in the drawings, 1 is the body of the bottle having the lower portion 2 of its neck made integral with the body and the upper portion 3 made in a separate piece and united with the part 2 by a thin metal sleeve 4 and a thin layer of cork 5. The two parts of the neck are formed with annular recesses 6 into which the sleeve 4 is pressed, the parts of the neck being joined together

after the bottle has been filled and the valve device has been inserted within the neck portion 2.

The invention resides in the construction 55 and arrangement of the valve device which consists of the valve case and valve. The valve case is a tubular casting of glass or other fictile material, being open from end to end. The upper portion 7 has a solid 60 imperforate side wall and the lower portion 8 is in the form of a ring. The intermediate portion of the valve case is in the form of separated rings 9 which are united together and with the upper and lower portions 7 65 and 8 by four longitudinal ribs 10. The valve case is of less diameter than the internal diameter of the neck so as to leave between the two a flow space for the liquid, and tapers slightly from its upper to its 70 lower end. It is suitably supported within the neck so as to be readily adjusted therein. For this purpose, the neck of the bottle preferably has a contracted portion 75 11 at its base which provides the support for the case, no open space being permitted between the base of the neck and the part 8 of the case, so that the liquid is compelled to flow out through the bore of the part 8. This part 8 is provided with a flange 12 80 and immediately beneath it and surrounding the part 8 is a ring of packing or gasket 13, preferably of cork. The upper end of the case is closed by a removable glass cap 14. Before the cap is put in place the valve 15, 85 made of glass or other fictile material and in the form of a solid piston, is inserted within the case. The cap is provided with a central projection 16 surrounded by a ring of packing or gasket 17, preferably made of 90 cork, which fits within the upper end of the case and holds the cap in place by friction after the parts of the valve device have been fitted together and before they have been inserted within the neck of the bottle. The 95 cap is provided with a series of radial projections 18 which extend slightly beyond the outer surface of the case.

An internal shoulder 19 on the upper part 3 of the neck contacts with the projections 100 18 of the cap and thereby securely holds the cap and case in place. The seat for the valve

is formed directly in the part 8 of the valve case itself and, in the preferred arrangement, the valve seat is tubular and tapering and the head 20 of the valve is cylindrical and tapering. The valve seat, being formed directly in the case itself, may be readily ground to accurately fit the valve head. It is important from an economical standpoint that the valve seat be formed in the valve case itself rather than in the neck of the bottle because the case can be very accurately cast and ground, whereas, it would be difficult and expensive to form a suitable valve seat in the neck of the bottle. The valve being made of solid glass is of suitable weight to readily open and close by gravity. The upper end of the valve is provided with a narrow bead 21 which closely fits the bore of the valve case. Between this bead and the valve head the valve is slightly reduced in diameter to allow space for the liquid to flow out between the valve and the case when the valve is open.

In order that the valve may be closed with certainty, when in horizontal position, a coil spring 22 made of fine oxidized copper wire is located within the case between the cap 14 and the upper end of the valve. The upper part 7 of the case is provided on its exterior with two opposite transverse projections 23 and 24 and beneath these projections 23 and 24 are two similar opposite projections 25 and 26, the upper and lower projections being placed in staggered arrangement with reference to each other. These projections are provided to prevent the access of a wire or other instrument to the valve should any attempt be made to insert such an instrument between the case and the neck to hold the valve open when the bottle is in upright position with the intent to surreptitiously refill the bottle. The bottle is provided with the usual sealing cork 27.

In using the invention the sealing cork 27 is first extracted and the bottle may then be canted to pour out its contents. When thusly canted, the valve 15 moves from its seat by its own weight and the liquid flows out freely around the valve, thence through the apertures between the rings 9 of the valve case, thence along the neck of the bottle and outside of the valve case and finally through the spaces between the radial projections 18 of the cap. When the valve moves back from its seat the bead 21 slides on the inner surface of the part 7 of the valve case and keeps the upper end and stem of the valve centered in the valve case so that the liquid may flow around the valve stem and out between all the rings of the valve case. The flow of the liquid is indicated in Fig. 2 of the drawings.

What I claim is:

1. In a non-refillable bottle, the combina-

tion with the neck having contracted portions near its upper and lower ends; of a tubular valve case within and partially filling the neck, said valve case having an upper imperforate portion, an intermediate perforate portion and a lower imperforate portion and supported by the lower contracted portion of the neck; a conical valve seat in said lower portion of the valve case; a valve within the case, said valve having a conical head and an elongated stem of less diameter than the internal diameter of the intermediate and upper portions of the valve case to permit outflow of liquid above the valve head when the valve is in open position; a coiled spring within the valve case and above the valve to assist the latter to its seat, said spring and valve being so proportioned that the spring closes the valve when the bottle is in horizontal position and the valve by its own weight opens against the spring when the bottle is tilted slightly below horizontal position; a removable cap to close the upper end of the valve case and held in place by the upper contracted portion of the neck, said neck being made in two parts permanently united by an external sleeve to permit the insertion of the valve case and cap.

2. In a non-refillable bottle, the combination with the neck having contracted portions near its upper and lower ends; of a tubular valve case within and partially filling the neck, said valve case having an upper imperforate portion, an intermediate perforate portion and a lower imperforate portion and supported by the lower contracted portion of the neck; a conical valve seat in said lower portion of the valve case; a valve within the case, said valve having a conical head and an elongated stem of less diameter than the internal diameter of the intermediate and upper portions of the valve case to permit outflow of liquid above the valve head when the valve is in open position; a coiled spring within the valve case and above the valve to assist the latter to its seat, said spring and valve being so proportioned that the spring closes the valve when the bottle is in horizontal position and the valve by its own weight opens against the spring when the bottle is tilted slightly below horizontal position; a removable cap to close the upper end of the valve case and held in place by the upper contracted portion of the neck, said neck being made in two parts permanently united by an external sleeve to permit the insertion of the valve case and cap, said valve case and valve each being made of fritile material and cast in one piece.

3. In a non-refillable bottle, the combination of a tubular valve case of fritile material cast in one piece and comprising an upper imperforate portion, an intermediate

perforate portion and a lower imperforate portion, said intermediate portion consisting of separated parallel rings united together and to the upper and lower portions of the valve case by ribs; a valve seat in the lower imperforate portion of the valve case; and a cap to close the upper end of the valve case having projections extending beyond the periphery of the valve case.

This specification signed and witnessed 10
this 22 day of November, 1913.

VIOLA A. S. THOMPSON,

*Administratrix of the estate of William F.
Thompson, deceased.*
